UNITED STATES PATENT OFFICE.

WALTER S. LANDIS, OF NIAGARA FALLS, NEW YORK, ASSIGNOR TO AMERICAN CYANAMID COMPANY, OF NASHVILLE, TENNESSEE, A CORPORATION OF MAINE.

PROCESS AND APPARATUS FOR FIXING ATMOSPHERIC NITROGEN.

1,103,061.

Specification of Letters Patent. Patented July 14, 1914.

Application filed April 3, 1914. Serial No. 829,332.

To all whom it may concern:

Be it known that I, WALTER S. LANDIS, a citizen of the United States, residing at Niagara Falls, in the county of Niagara and State of New York, have invented certain new and useful Improvements in Processes and Apparatus for Fixing Atmospheric Nitrogen; and I do hereby declare the following to be a full, clear, and exact 10 description of the invention, such as will enable others skilled in the art to which it app pertains to make and use the same.

This invention relates to a process of and apparatus for fixing atmospheric nitrogen and has for its object to improve the present commercial processes and furnaces now employed in the cyanamid industry, by rendering the same more efficient in action and less costly to operate.

With these and other objects in view the invention consists in the novel steps constituting my process and in the novel combinations of parts constituting my apparatus, all as will be more fully hereinafter disclosed and particularly pointed out in the claims.

Referring to the accompanying drawings forming a part of this specification in which like numerals designate like parts in all the views—Figure 1 is a diagrammatic sectional view of a furnace or cyanamid forming can made in accordance with my invention; Fig. 2 is a cross sectional view of the parts shown in Fig. 1, and disclosing a slightly modified form of the apparatus, while Fig. 3 is a view similar to Fig. 2 but showing a still further modified form of the apparatus.

1 indicates any suitable outer casing or container, 2 an inner can or container of conducting material for holding the carbid, 3 a resistor preferably made of carbon buried directly in the mass of carbid 10, and out of direct contact with the excess of nitrogen circulating through the interstices, while 4 is a second resistor likewise directly buried in the mass of the carbid 10 and out of direct contact with the circulating excess of nitrogen through said mass.

5 and 6 represent suitable lead wires for the current, 7 a suitable cover for the vessel 1 and 11 any suitable means for leading nitrogen into the vessel 1 and into contact with the carbid 10.

12 represents any suitable means for pre-

venting the oxidizing effect of the impurities carried by the nitrogen from destroying the resistor. In the instance shown the means employed is an enlarged upper end for the resistor, which may be either integral with the resistor or it may be simply an enlarged mass of graphite into which the resistor is suitably connected as by coarse threads or by other means. The manner in which the enlarged head 12 prevents the oxidizing effect from destroying the resistor is as follows. The said head 12 being at a lower temperature than the rest of the resistor the oxidizing effects thereon are not as great as they would be if the said head were at a higher temperature. Further the said head 12 being of a larger diameter than the rest of the resistor, it takes a longer time for it to be eaten away than is the case with the smaller cross section of the resistor. In practice I choose the head of a diameter sufficiently large to last through the entire run, so that the resistor is not destroyed, as will appear more fully below.

In my copending application entitled "Method of and apparatus for fixing nitrogen," filed on the 3rd day of April, 1914, Serial No. 829,337, I have disclosed a method and an apparatus for starting a reaction between the nitrogen and the carbid similar to the method which is disclosed below, but in that case only a single resistor is employed instead of a plurality of resistors as is the case here.

In that case I have further found that the reaction itself starts from a centrally heated point close to the resistor, and moves concentrically outward, while the supply of nitrogen through the mass moves inwardly through the mass and through the unreacted carbid until it reaches said concentrically outwardly moving zone of reaction. But as this carbid is very finely ground and packs very closely in the vessel containing it, this inward flow of nitrogen to the reacting outwardly moving surface is very slow, because of the high resistance to the passage of the nitrogen which is offered by this finely ground carbid. As a result the time of nitridation of a single furnace charge of carbid employing a single resistor is greatly prolonged over what it would be if two or more resistors are employed. I have accordingly discovered that it is very advantageous to insert in each furnace charge a plurality

of resistors thus starting a reaction from the several resistors at the same time and thus materially decreasing the length of the path over which the nitrogen must flow through the fine carbid and I am enabled thereby to greatly hasten the nitrification of the charge.

In the drawings I have diagrammatically illustrated by the dotted lines 15 what might be considered the elements of the outwardly moving zones of reaction at a given time, while by the dotted lines 16 I have likewise illustrated what might be considered the outward elements of the zones of reaction after a further time has elapsed.

From the dotted lines 16 it will be clear that the zones of reaction will soon overlap each other so that there will be very little unreacted carbid left and as a matter of fact experience shows that a given quantity of cyanamid is made in a very much less time with a plurality of resistors than is possible with a single resistor. For example, when four resistors are used as is shown in Fig. 2 it is a comparatively short time before practically all of the carbid has been reacted upon, because there are four zones of reaction moving outwardly at the same time through the mass. In the case of the old method wherein a central core was used such a result was impossible and for the reason that the central core had to be of such a volume that it reduced materially the quantity of carbid treated in each furnace and with three or four such cores in the furnace the waste volume was so high that the product produced was cut down to such an extent that the process was no longer commercial. By burying the resistors however directly in the mass as herein disclosed only a very small amount of carbid is displaced by said resistors on account of their small size and therefore no appreciable loss of product is experienced as was the case with a plurality of cores. Further it is self-evident that no appreciable additional quantity of energy is required with a plurality of resistors and that therefore no additional expense is made on this score. An additional advantage of a plurality of resistors over a single resistor such as is disclosed in my copending application above referred to resides in the fact that when a single resistor is used in the center of the can its heating effect very rapidly drops off as the reacting zone travels outward and therefore if a given area of reacting zone at some distance from the resistor is considered only a small fraction of the heat that is applied to this same area at a point close to the resistor is found to be concentrated at the distant point. Therefore the use of a single resistor is really limited to a certain definite zone of action, because if one exceeds this limit the temperature at the sur-

face of the active reacting zone drops to such a point that the reaction is no longer efficient. With a number of resistors on the other hand they can be so located that no point of the mass of carbid is so distant from one or more of the said resistors that the temperature will fall so low as to render the reaction inefficient. It therefore follows that for a given output or size of furnace can a plurality of resistors produce a much more complete reaction throughout the entire mass than when only a single resistor is used, and further larger amounts or masses of carbid can be reacted on at the same time. In other words not only is a greater efficiency of nitrogen fixation obtained with the same energy when a plurality of resistors is used, but the use of a plurality of resistors enables me to greatly enlarge the capacity of each furnace.

In the modified form of my invention illustrated in Fig. 3 I have shown six resistors, which enable me to produce a high efficiency of nitrification, and also to greatly enlarge the size of the can. But in such case I further prefer to leave a hollow opening or core 8 for the passage of the nitrogen through the center of the mass, in order that the nitrogen may not only freely flow up through the center of the mass and thereby reach the reacting zones from the center toward the surface, but may also flow through the annular space 17 from the outer surface of the mass toward the center. In some cases I may even place extra resistors in the mass for use should one or more of the active resistors become damaged or inactive for any reason. These extra resistors are very convenient in very large furnaces, for in such cases I can make use of one or more of these said extra resistors and still maintain the same heat without stopping the operation. Of course these said resistors may be connected to the lead wires either in multiple or in series without departing from the spirit of my invention. In other words it is obvious that those skilled in the art may vary the steps of my process, as well as the details of my construction without departing from the spirit of my invention and therefore I do not wish to be limited to the above disclosure except as may be required by the claims.

What I claim is.

1. The process of fixing atmospheric nitrogen which consists in providing a charge of carbid; feeding nitrogen to said charge; burying directly in said charge a plurality of resistors; and raising said resistors to the temperature necessary to bring about the desired reaction, substantially as described.
2. The process of fixing atmospheric nitrogen which consists in providing a charge of carbid; feeding nitrogen to said charge; burying directly in said charge a plurality

of resistors; preventing oxidizing effects from destroying the exposed portions of said resistors not so buried; and raising said resistors to the temperature necessary to bring about the desired reaction, substantially as described.

3. In an apparatus for fixing atmospheric nitrogen the combination of an outer vessel; an inner vessel adapted to hold a charge of carbid; means for feeding nitrogen to said charge; and a plurality of resistors directly buried in said charge, substantially as described.

4. In an apparatus for fixing atmospheric

nitrogen the combination of an outer vessel; 15 an inner vessel adapted to hold a charge of carbid; means for feeding nitrogen to said charge; and a plurality of resistors provided with enlarged upper ends and directly buried in said charge, substantially 20 as described.

In testimony whereof I affix my signature, in presence of two witnesses.

WALTER S. LANDIS.
